CIGARETTE HOLDER

Walter W. Brady, Alhambra, Calif., assignor of
one-half to Charles A. Foley, Phoenix, Ariz.

Application October 29, 1938, Serial No. 237,731

1 Claim. (Cl. 131—175)

The present invention relates to new and useful improvements in cigarette holders and has for its primary object to provide, in a manner as hereinafter set forth, a device of this character embodying novel means for preventing the dropping of ashes, sparks, etc.

Other objects of the invention are to provide a cigarette holder of the aforementioned character which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a cigarette holder constructed in accordance with the present invention.

Figure 2 is a top plan view, showing the device open with a cigarette therein.

Figure 3 is a cross sectional view, taken substantially on the line 3—3 of Fig. 1.

Figure 4 is a cross sectional view, taken substantially on the line 4—4 of Fig. 2.

Figure 5 is a longitudinal sectional view through the inner end portion of the device.

Referring now to the drawing in detail, it will be seen that the embodiment of the invention which has been illustrated comprises a bit or mouthpiece 1 of suitable material. The mouthpiece 1 has extending longitudinally therethrough a smoke passage 2. Projecting longitudinally from the forward end of the mouth-piece 1 is an integral nipple 3 the inner portion of which is externally threaded. Extending into the nipple 3 is a socket 4 for the reception of a cigarette, as at 5 (see Fig. 2). The socket 4, of course, communicates with the smoke passage 2.

Mounted on the mouthpiece 1 is a guard which is designated generally by the reference numeral 6. The guard 6 includes elongated complementary half sections 7 and 8 which are hingedly connected on one side, as at 9. The half sections 7 and 8 of the guard 6 are provided with fireproof linings 10 of suitable material, such as asbestos. As shown to advantage in Figs. 1 and 2 of the drawing, the guard sections 7 and 8 are perforated, as at 11, for the entrance of air.

Fixed in the inner end portion of the guard section 7, which is stationary, is an internally

threaded ring 12 (see Fig. 5) which is threaded on the nipple 3. Thus, the guard 6 is mounted on the mouthpiece 1. At its outer end the guard 6 is closed, this end of said guard being rounded in the manner shown to advantage in Fig. 1 of 5 the drawing.

Projecting from the hingedly connected sides of the guard sections 7 and 8 is a pair of diverging handles or levers 13 of substantially the shape shown to advantage in Fig. 1 of the drawing. 10 The outer end portions of the levers 13 have formed therein and extending thereacross slight grooves or channels 14. Mounted between the levers 13 is a spring 15 for closing the guard 6. As best seen in Fig. 3 of the drawing, the end portions of the spring 15 are engaged in the grooves or channels 14 for securing said spring in position between the levers 13. 15

It is thought that the manner in which the device is used will be readily apparent from a 20 consideration of the foregoing. For the insertion of a cigarette, or the removal of a cigarette stub, the guard may be conveniently opened by pressing the levers 13 together against the tension of the spring 15. Of course, as soon as the levers 25 13 are released the spring 15 functions to close the guard 6. Ashes and sparks dropping from the burning cigarette are caught and retained in the asbestos lined guard 6. The guard 6 also permits the device to be placed in a pocket with 30 safety with a burning cigarette therein. It may be well to here state that the device may be readily made to accommodate cigars as well as cigarettes.

It is believed that the many advantages of a 35 cigarette holder constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed. 40

What is claimed is:

A cigarette holder of the class described comprising a mouthpiece having a smoke passage 45 therein, an integral externally threaded nipple projecting longitudinally from the forward end of said mouthpiece, said nipple having a socket 50 therein communicating with the smoke passage for the reception of the cigarette, an internally threaded ring threaded on the nipple, a perforated guard including two half sections, the inner ends of which are straight and the outer ends of which are rounded, the straight inner end of 55

one section being fastened to one-half of the exterior circumference of the ring, hinge means for connecting a side edge of the movable half section to the stationary half section, perforated linings in the two sections of fireproof material, the inner end of each lining terminating at the front face of the ring, handles connected to side

portions of the two sections adjacent side edge portions thereof, and spring means extending between the handles for holding the movable section against the stationary section, the linings having perforations therein registering with the 5 perforations in the sections.

WALTER W. BRADY.
